DES 674 10-17-1854

Des. 674

W^m.th Gray, of Philadelphia, Pa.

Assignor to,

Dr. Hagar & Co. of Philadelphia, aforesaid.
Letters Patent No. 674 Dated Oct. 17th 1854.

The schedule referred to in these Letters Patent and making part of the same.

To all whom it may concern.

Be it known, that I, William P. Gray, of the City and
County of Philadelphia, and State of Pennsylvania, have produced a new and original
Design for cook stoves called the "Atlantic"

and I do hereby declare that the following is a full, clear, and exact description of the
same reference being had to the annexed drawings forming part of this specification, in which
Figure 1. is a front elevation of the stove.

Figure 2. is a side elevation of the same.

Similar characters of reference in the several figures denote the
same part of stove and design.

The front of this stove which is of a swell form comprises the doors
A A' & B B' and band C, between the two pairs of doors the former of which

A, A' are surrounded by a bead a, and have their entire surfaces studded with the semi-spherical projections c, arranged in rows as shown in the drawing. The doors B, B' form a connection between the curved band C and the top moulding D, and are of the cima reversa form rounded at the outer corners. The band C, bears the word "Atlantic" in raised capitals together with the number of the stove. The arrangement and configuration of the entire front being as delineated and set forth in figure 1.

The side plates E are each surrounded by a moulding F, and each bears the oven door G, and panel H, the former so designed as to have the appearance of bearing two panels H' H'', similar to the panel H, producing the effect of each side plate having three raised panels of equal size, each panel surrounded by a moulding I, and studded with semi-spherical projections i, like the projections c, on the front doors A, A'. On one side, the upper portion of the panel H, forms a door, which when closed gives the same appearance to both sides of the stove. Above the panels H H' H'' is the inclined tablet P, along the lower edge of which and also within the moulding F are the projections e. The design configuration and arrangement of the several ornaments and mouldings of the sides of the stove are fully set forth in figure 2. of the drawing.

The upper portion of the foot R, is rounded and bears the two rows of pear shaped projections r, the bead s, and groove t, so arranged as to give that portion of the foot the scroll form shown in the drawing. Beneath this projecting upper portion is the foliated band T, composed of the leaves m, n, o, from which issues by a graceful curve, the lower portion or paw of the foot; the design, configuration and arrangement of the several parts being as set forth in figure 3.

What I claim as my invention or production, is

The design, configuration, and arrangement of the several ornaments in bas-relief, and mouldings on the front, sides and feet of the stove "Atlantic" as herein fully set forth and delineated in the annexed drawings.

In testimony whereof I have hereunto signed my name before two
subscribing witnesses.

Witnesses,

O. Brazer
Jacob Freas
